[57] CLAIM

The ornamental design for a magnetic disc drive housing, as shown and described.

DESCRIPTION

FIG. 1 is a top, front left side perspective view of a disk drive housing showing my new design;

FIG. 2 is a top plan view thereof on an enlarged scale;

FIG. 3 is a bottom plan view thereof on an enlarged scale;

FIG. 4 is a left side elevational view thereof on an enlarged scale;

FIG. 5 is a right side elevational view thereof on an enlarged scale;

FIG. 6 is a front elevational view thereof on an enlarged scale;

FIG. 7 is a rear elevational view thereof on an enlarged scale.
